UNITED STATES PATENT OFFICE.

CARLETON ELLIS, OF LARCHMONT, NEW YORK, ASSIGNOR TO CHADELOID CHEMICAL COMPANY, OF NEW YORK, N. Y., A CORPORATION OF WEST VIRGINIA.

PROCESS OF APPLYING PAINT-REMOVERS.

No. 875,163.

Specification of Letters Patent.

Patented Dec. 31, 1907.

Application filed August 6, 1907. Serial No. 387,275.

To all whom it may concern:

Be it known that I, CARLETON ELLIS, a citizen of the United States, and residing at Larchmont, Westchester county, New York, 5 have invented a new and useful Improvement in the Process of Applying Paint-Removers, of which the following is a specification.

My invention relates to a method of applying substances of a liquid or semi-liquid consistency to painted or varnished surfaces to soften or dissolve the finish coating thereon, and thus to render possible the ready removal of the same.

15 All classes of liquid removers come within the scope of my invention, acid, alkaline and neutral, but I have in mind more particularly in this connection the use of neutral removers which depend for their efficiency 20 upon the presence of volatile solvents. Hitherto it has been customary to apply such removers to surfaces by the agency of an ordinary paint brush. The disadvantages of this method are obvious. The use of an un- 25 covered can and the necessity of moving the brush frequently to and from the can to obtain fresh amounts of the remover and apply the same to the surface being treated are sources of continual loss of the volatile sol- 30 vents by evaporation. The necessity also by this method of applying the fresh amounts of remover to the exterior rather than the interior of the brush accentuates the loss by evaporation. By my invention 35 I avoid all of these disadvantages. To accom- plish this end, my remover, which consists of one or more volatile solvents, such as benzol, alcohol, etc., and preferably a thick- 40 ening material more or less soluble therein, as wax, which may be present in a minimum quantity of 3 or 4 per cent., is forced under pressure in any desired manner, as by means of air pressure or a hydraulic head, into the interior of a curtained sprayer or atomizer.

45 The curtain of the device is designed to be brought into contact with the surface to be treated. In this position it effectively prevents any loss of the remover by splashing or evaporation, and at the same time operates 50 to smooth out and render the layer of liquid of a uniform thickness on the finish coated surface. It will be seen that in a process of this character, the curtained sprayer being directly connected by a flexible hose to a cov- 55 ered supply tank, all evaporation and loss of

the solvent is effectively prevented. So that, as a consequence, the paint remover when it reaches the surface to be treated contains all of even its most volatile constituents and is thus in a condition to most effectively and 60 most rapidly soften the finish coating being operated upon.

I construct the curtain above referred to either out of bristles which of course would have a maximum smoothing effect, or out of 65 a woven fabric, rendered impervious to fluids or not, as may be desired, which would have a maximum evaporation retarding effect, but preferably out of a combination of the two. That is to say, I provide various 70 forms of bristle brushes, the layers of bristles of which are retained in position and at the same time assisted in the retarding of evaporation by outer curtains of woven fabric.

I have hereinafter described the details of 75 my process, and I have shown the structure of the apparatus which I use in carrying out the same, in the accompanying drawings, in which

Figure 1 is a vertical cross-sectional view of 80 my preferred brush; Fig. 2, a similar section of another form of brush; Fig. 3, a horizontal cross-section of the brush shown in Fig. 2; Fig. 4, a horizontal cross-section of Fig. 1; Fig. 5, an elevation, showing a different ar- 85 rangement of the curtains in the brush; Figs. 6 & 7, vertical cross-sections of still other arrangements of the curtains; and Fig. 8, a view of the entire apparatus on a very much 90 smaller scale.

In Figs. 1 and 4, 1 indicates a brush handle having a longitudinal channel 2 therein, provided with a gate-valve 3. The channel 2 opens into a horizontal chamber 4, located in the cylindrical brush stock 5, which is screw-threaded to the handle 1. This chamber is provided with a number of circularly arranged vertical outlets or nozzles 6 and a central outlet 6', the mouths of which are flared, as at 7. In the spaces between the circularly 95 arranged outlets are located a number of concentric annular curtains, each one of which consists of an outer layer of fabric 8, rendered impervious to liquids or not, as may be desired, and preferably of a woven character, 100 such for example, as hair-cloth, and an inner annular layer of bristles 9. Wherever I use bristle curtains, however, I take care to construct them in such a way as to produce a 105 solid continuous wall of bristles.

- Figs. 2 & 3 show another modification differing in that there is only a single curtain of fabric and bristles which in this case is flattened at 10 and tapered at its lower end 11, 5 and in the fact that the outlets 12 are located in a straight line instead of circularly. These outlets are connected to the main longitudinal channel by a horizontal chamber similar in construction to that in Fig. 1.
- 10 Fig. 2 shows the detailed construction of the valve 3, which is an ordinary gate valve provided with the valve-plate 13 sliding in the chamber 14 and connected to the spring retracted button 15 by means of the rod 16 15 passing through a stuffing box 17.
- Fig. 5 shows an external view of either a cylindrical or flattened brush such as those shown in the preceding figures, but with the outer fabric curtain 18 shortened.
- 20 Fig. 6 shows a cylindrical brush identical in construction with the brush in Fig. 1, but the curtains 19 of which are made of bristles alone.
- Fig. 7 shows a brush of the same character, 25 but with the curtains 20 made entirely of fabric.
- Fig. 8 shows the entire apparatus used for applying the remover. In this figure, 21 is a pressure supply-tank for the liquid remover, 30 22 a flexible hose made of some material which is not affected by the volatile solvents, such as metal, and 23 the curtained sprayer or atomizer for applying the material directly to surfaces.
- 35 In operation the process is carried out briefly as follows: The liquid remover being supplied by pressure from the tank 21 to the supply pipe 22 is forced into the handle of the curtained sprayer. Upon the depression of 40 the button 15, the liquid is allowed to pass in any desired quantity, according to the extent to which the valve has been opened by the operator, into the horizontal chamber 4 and thence through the nozzles 6, 6' where 45 the material is sprayed or atomized and projected upon the surface being treated. The bristle curtains are especially advantageous in producing a layer of remover of an even thickness owing to their effective spreading 50 action. The other curtains made of fabric are useful as they more effectively prevent the evaporation of the volatile solvents. In order to secure the advantages of both of these, I have constructed the preferred modification of the curtained sprayer with curtains of both kinds. It should be noted that in the use of the modification shown in Fig. 55 the outer, shorter curtain 18 is brought into close proximity to the surface being treated owing to the fact that the protruding ends of the bristles readily bend over under pressure. If at any time in the operation of the device 60 the openings 6, 6' should become clogged, they can be readily cleaned by the insertion

of a wire or similar instrument. I have provided the openings with flaring mouths 7 so that an instrument of this kind can be inserted without difficulty.

It will be seen that by my process the paint or varnish remover containing volatile components is conveyed from the supply tank and applied to the surface under treatment without any loss whatever. The supply tank is covered and has its only outlet through the supply pipe. The liquid being conveyed to the spraying or atomizing nozzles by the supply pipe, is projected therefrom upon the finish-coated surface inside of a continuous annular curtain of bristles or fabric or both, which effectively prevents any loss by evaporation as well as intercepts and returns to the surface under treatment any portions of the liquid that may have rebounded therefrom by splashing. When the curtain is made of woven fabric and has been treated to render it impervious to liquids, any escape of the remover through it is, of course, absolutely prevented. But even when using a curtain of this kind, which has not been so treated, and in the use of a bristle curtain merely, enough solid matter is deposited thereon in the course of a short while to prevent substantially entirely the passage of any part of the fluid solvents.

What I claim and desire to cover by Letters Patent is:

1. A process of the character described, consisting in conveying the liquid paint or varnish remover from a source of supply, 100 then applying it to the surface to be treated without the escape of any part thereof.
2. A process of the character described, consisting in conveying the liquid paint or varnish remover from a source of supply, 105 then applying it to the surface to be treated without the loss of any part thereof by evaporation.
3. A process of the character described, consisting in conveying the liquid paint or 110 varnish remover from a source of supply, then projecting it upon the surface to be treated while preventing any loss by splashing.
4. A process of the character described, 115 consisting in conveying the liquid paint or varnish remover from a source of supply and applying it to the surface to be treated by passing it through a covered passageway so as to avoid any loss by evaporation, splashing or otherwise.

In testimony whereof, I have hereunto signed my name in the presence of two witnesses.

CARLETON ELLIS.
